COMB CLEANER

Emil Troendle, Apopka, Fla.

Application December 12, 1950, Serial No. 200,413

2 Claims. (Cl. 15—39)

1

This invention relates to comb cleaners of the type wherein combs are passed through or between rotating brushes, and in particular a comb cleaner wherein pairs of brushes are positioned in meshing relation with the ends of the bristles of cylindrical brushes on one side of an open passageway interlocked with or extended into the ends of bristles of a complementary pair of rollers so that as a comb is forced between the rollers the bristles are forced into the areas between the comb teeth with the result that a comb passed through the rollers is efficiently cleaned.

The purpose of this invention is to provide an improved comb cleaner wherein a comb is not only brushed off but is cleaned by the ends of a plurality of bristles being forced into the areas between the comb teeth.

Various arrangements of rotary brushes have been provided for cleaning combs but where the edges of the brushes meet at the center there is not sufficient pressure to force the bristles into the areas between the comb teeth and for this reason comb cleaners of this type are not universally used.

With this thought in mind this invention contemplates a pair of housing sections with pairs of rotary brushes journaled in spaced faces of the sections and with means for mounting the sections in abutting relation with bristles of brushes on one side extended into bristles of brushes on the other side or section and wherein a comb passed through the brushes is thoroughly cleaned.

The object of this invention is, therefore, to provide means for mounting pairs of rotary brushes whereby bristles of brushes of one pair mesh with and extend into bristles of brushes of another pair so that the bristles of the brushes are forcibly urged into areas between teeth of a comb passed through the brushes.

Another object of the invention is to provide an efficient comb cleaner that may be used on a stand or in the palm of the hand.

The further object of the invention is to provide a comb cleaner having bristles of pairs of brushes in meshing relation which is of a simple and economical construction.

With these and other objects and advantages in view the invention embodies a pair of substantially hollow casings having arcuate inner and outer surfaces with rollers journaled in the casings and with grooves in the backs of the casings by which the casings are removably supported on stands.

Other features and advantages of the inven-

tion will appear from the following description taken in connection with the drawings wherein:

Figure 1 is an end elevational view of the comb cleaner.

Figure 2 is a cross section through the comb cleaner with the parts positioned as shown in Fig. 1.

Figure 3 is a plan view of the comb cleaner.

Figure 4 is a side elevational view showing the comb cleaner.

Figure 5 is a plan view of the comb cleaner.

Figure 6 is an end elevational view illustrating a modification of the comb cleaner wherein the brush mounting elements extend outwardly as illustrated in Fig. 8 or downwardly as illustrated in Fig. 7.

Figure 7 is a side elevational view of the comb cleaner shown in Fig. 6.

Figure 8 is a side elevational view of a comb cleaner showing a further modification wherein the cleaner elements are suspended by a wall bracket with the parts mounted on parallel outwardly extended arms.

Referring now to the drawings wherein like reference characters denote corresponding parts the improved comb cleaner of this invention includes rotary brushes 10 and 11 which are mounted in a facing section 12 of a case 13 and similar brushes 14 and 15 that are mounted in a facing section 16 of a case 17.

The rollers 10 and 11 are provided with mounting shafts 18 and 19, respectively and the brushes 14 and 15 are provided with mounting shafts 20 and 21, respectively. The shafts 18 and 19 are journaled in the ends of the facing section 12 and the ends of the shafts 20 and 21 are journaled in the ends of similar sections 16.

The casing 13 is provided with a recess in the back having grooves 22 and 23 that are positioned to receive tongues 24 and 25, respectively on a mounting bar 26 and the casing 17 is provided with similar slots 27 and 28 that are positioned to receive tongues 29 and 30, respectively on a mounting bar 31.

The bars 26 and 31 are provided with recesses 32 and 33, respectively and the inner walls 34 and 35 of the casings 13 and 17 are provided with projections 36 and 37, respectively that snap into the recesses 32 and 33, thereby providing means for retaining the bars in operative position.

The bars 26 and 31 extend upwardly from a base 38 being carried on the upper ends of plates 39 and 40 and the plates 39 and 40 are provided

with extensions or clips 41 and 42 which provide racks for holding combs and the like.

As illustrated in Fig. 3 the ends of the casing 13 are provided with ribs 45 and 46 and the ends of the casing 17 are provided with similar ribs 47 and 48.

In the design illustrated in Figs. 1, 2, 3 and 4 the supporting bars 26 and 31 are mounted on the panel or base 38 and in the design illustrated in Figs. 6, 7 and 8 the casing sections 13 and 14 are carried by tongues 49 and 50 which extend outwardly from a base 51 with the tongues connected to the base through sections 52 and 53 and, as illustrated in Fig. 7 the sections 52 and 53 are provided with bars 54 and 55, respectively, that are spaced from the tongues 49 and 50. The base 51 is provided with openings 56 for screws, as indicated by the dotted line 57, in Fig. 6.

The base 51 may be attached to the under side of a cabinet, shelf, or other surface, or the base 20 it may be turned over to the position shown in Fig. 8 and attached to the face of a wall, or the like.

The comb cleaner of this invention may, therefore, be positioned with the rotary brush mounting sections extended upright as illustrated in Figs. 1 and 2 or the comb sections may be held in the hand with the mounting elements omitted, as illustrated in Fig. 5 or the sections may be carried on a wall bracket or suspended from a base as illustrated in Figs. 6, 7 and 8.

The brushes may be formed of any suitable material however, it is preferred to form the mounting elements of plastic and the bristles of the brushes of nylon.

With the brush housings or casings 13 and 17 provided with removable facing plates 12 and 16, respectively, the housings may readily be opened for cleaning.

It will be understood that modifications may be made in the design and arrangement of the parts without departing from the spirit of the invention.

What is claimed is:

1. In a comb cleaner, the combination which comprises a pair of elongated hollow casings having front and rear walls, said casings being positioned so that the front walls thereof are in spaced parallel relation to each other, there being openings in the front walls and longitudinally disposed recesses with grooves in the edges thereof in the rear walls, pairs of cylindrical brushes journaled in said casings for relative rotation with regard to each other and with bristles of the brushes extended through the openings of the front walls thereof, a base, and bars having tongues on the edges thereof extended into the grooves of the recesses in the rear walls of the casings mounted on the said base, said base and bars positioning said casings with bristles of the brushes of one casing extended into bristles of the brushes of the other casing.

2. A comb cleaner as in claim 1 wherein the front walls are removable from the casings whereby the casings may be readily opened for the purpose of cleaning.

EMIL TROENDLE.
